E. OHNSTRAND.
LOCK FOR FIREPROOF STRUCTURES
FILED OCT. 6, 1921.

FIG. 2.

FIG. 1

Inventor:
Enoch Ohnstrand
By Olof Gustaf Sundman
his Atty.

UNITED STATES PATENT OFFICE.

ENOCH OHNSTRAND, OF MOHAWK, NEW YORK, ASSIGNOR TO LIBRARY BUREAU, OF CAMBRIDGE, MASSACHUSETTS, A CORPORATION OF NEW JERSEY.

LOCK FOR FIREPROOF STRUCTURES.

Application filed October 6, 1921. Serial No. 505,685.

To all whom it may concern:

Be it known that I, ENOCH OHNSTRAND, a citizen of the United States of America, and resident of Mohawk, in the county of Herkimer and State of New York, have invented new and useful Improvements in Locks for Fireproof Structures, of which the following is a specification.

This invention relates to fire-proof and fire-resisting structures, such as cabinets, vaults and the like, and to improved locks therefor having means for preventing the access of sufficient heat to the interior of such structures to damage the contents thereof.

15 In constructing structures of this kind, particularly fire-resisting cabinets, an opening is ordinarily left through the insulation of the door for the installation of the lock which is inserted from the back. The usual 20 lock comprises a casing for the bolt mechanism mounted on the inside of the door and connected by means of a tubular connector to the dial plate on the outer side of the door, an actuating rod extending axially 25 through the tubular connector to connect the actuating handle with the lock mechanism. The opening or hole through the door is larger than the cylindrical portion of the lock received therein to permit the passage 30 of a collar or other shoulder thereon which contacts the face plate of the door. In consequence thereof an air space of appreciable size extends through the insulation of the door, closed only by the actuator portion of 35 the lock upon the outside and by the bolt portion of the lock within, both of which are of metal, usually steel, and consequently good conductors of heat. When such a structure is subjected to high temperatures, 40 as in a fire, it has been found that the inner bolt portion of the lock sometimes becomes sufficiently hot to ignite inflammable material in contact therewith or otherwise damage the contents of the structure.

45 Objects of the invention are to prevent the inner portion of the lock on a fire-proof receptacle from being unduly heated, to reduce the conductive path between the inner and outer portions of the lock, and in general 50 to overcome the defects of previous devices of this kind.

The invention involves surrounding the actuating rod which extends from the bolt casing to the exterior of the structure with 55 insulating material. It further involves

means substantially filling the hollow connector extending from the bolt casing to the exterior of the structure to prevent radiation of heat longitudinally through the connector. This connector is preferably a tube, 60 but may be a skeleton structure made up of rods, either interconnected in the form of a lattice or separate. In particular the invention comprises a lock of the type referred to having as a part thereof insulation filling 65 the space between the connector and the actuating rod disposed therein, and also the space surrounding the connector. In the preferred embodiment of the invention the portions of the insulation inside and outside 70 the connector are integrally united together through openings in the connector, the openings further reducing the transfer of heat by reducing the cross section of the connector. The outer surface of the insulation 75 is preferably tapered as is also the opening through the door thereby to effect a closer fit between the insulation and the door, the central portion of which also comprises insulation.

In order to illustrate the invention one concrete embodiment thereof is shown in the accompanying drawing, in which—

Fig. 1 is a perspective view of a lock installed in the door of a fire-proof receptacle, portions of the receptacle being shown in section; and

Fig. 2 is a section on the line 2—2 of Fig. 1.

The lock comprises a bolt casing A having 90 a bolt a, an actuator or dial plate B, a dial b and a knob b', and a connector C interconnecting the bolt casing and dial plate. The connector C is attached to bolt casing A in any convenient and known manner, as by a 95 collar c of larger diameter than the connector. Upon connector C adjacent actuator plate B is a similar collar or abutment nut c' adapted to contact with the face plate D of the receptacle door. Bolt casing A of 100 the lock is almost wholly contained within the door, back plate E of the door contacting and holding it in place in any suitable manner, and connector C is received within the usual opening or hole F in the wall insulation G between plates E and D of the door.

While connector C between the portions A and B of the lock may be of any desired or suitable form, the preferred form shown 110

in the drawing is a tube having elongate slots c^2 , three in number, as shown in Fig. 2, but the number of slots may be increased or diminished at will provided the web portions of the connector are sufficiently strong for the purpose required. Within member C is a rod c^3 connecting the actuator or dial b with the mechanism in bolt casing A for actuating bolt a. The spaces between rod c^3 and connector C and between the tubular connector C and opening F in the walls of insulation G I fill by molding plastic insulating material about tubular connector C and forcing it through the slots c^2 therein so that a layer g is formed within the tube C completely surrounding rod c^3 . A similar layer of insulation g' is likewise molded about the exterior of the tube C between collars c and c' thereon, the insulation in the slots c^2 forming ribs g^2 uniting the two layers g and g' into an integral mass of insulation. This outer layer of insulation g' is preferably tapered toward the collar c' as clearly indicated in Fig. 1 to fit the correspondingly tapered opening F in the wall of insulation G in the receptacle door.

While a certain amount of heat will still be conducted within the receptacle by the metal connections between the dial and the lock proper in the improved lock, exhaustive tests have shown that the amount is not excessive. Slotting the tubular connector C to form a skeleton structure has done much to reduce even this amount. By filling connector C with insulating material and molding a layer thereon of sufficient thickness to fill the lock opening in the door, radiation and convection of heat from the actuator plate to the lock casing is effectively prevented.

I claim:

1. A lock for fire-proof structures comprising a bolt casing adapted to be mounted inside the structure, an actuating member extending from said casing to the outside of the structure, and insulating material surrounding said member and in contact therewith.
2. A lock for fire-proof structures comprising a bolt casing adapted to be mounted inside the structure, a hollow connector extending from said casing to the outside of the structure, and means substantially filling the hollow connector, whereby radiation of heat longitudinally through the connector is prevented, said means comprising actuating means for the lock and a layer of insulating material interposed between said actuating means and said connector.
3. A lock for fire-proof structures comprising a bolt casing adapted to be mounted inside the structure, a hollow connector extending from said casing to the outside of the structure, and means substantially filling the hollow connector, whereby radiation

of heat longitudinally through the connector is prevented, said means comprising an actuating rod and a layer of insulating material between said rod and said connector.

4. A lock for fire-proof structures having an opening therein comprising a bolt casing adapted to be mounted inside the structure, a connector extending from the casing through the opening in the structure to the inside thereof, and a covering of insulation fast on said connector whereby the latter with the insulation thereon may be inserted as a unit to fill said opening.

5. A lock for fire-proof structures having a tapered opening therein comprising a bolt casing adapted to be mounted inside the structure, a connector extending from the casing through the opening in the structure to the outside thereof, and a tapered covering of insulation fast on said connector shaped to fit and completely fill said opening.

6. A lock for fire-proof structures comprising a bolt casing adapted to be mounted inside the structure, a hollow connector extending from said casing to the outside of the structure, actuating means for said lock extending through said connector, and insulation covering the inside and outside of said hollow connector.

7. A lock for fire-proof structures comprising a bolt casing adapted to be mounted inside the structure, a hollow connector extending from said casing to the outside of the structure, actuating means for said lock within said connector said connector having openings therethrough, and insulation filling said openings and covering the inside and outside of said hollow connector.

8. A lock for fire-proof structures comprising a bolt casing adapted to be mounted inside the structure, a hollow connector extending from said casing to the outside of the structure, actuating means for said lock within said connector said connector having openings therethrough, and an integral body of insulation material filling said openings and covering the inside and outside of said hollow connector.

9. A lock for fire-proof structures comprising a bolt casing adapted to be mounted inside the structure, a hollow connector extending from said casing to the outside of the structure, an actuating rod extending longitudinally through said connector, said connector having openings therethrough, and insulation filling said openings and covering the outside of said connector and substantially filling the space between said connector and actuating rod.

10. A lock for fire-proof structures comprising a bolt casing adapted to be mounted inside the structure, a hollow connector extending from said casing to the outside of the structure, an actuating rod extending longitudinally through said connector, said

connector having openings therethrough, and an integral body of insulation filling said openings and covering the outside of said connector and substantially filling the space between said connector and actuating rod.

11. A lock for fire-proof structures comprising a bolt casing adapted to be mounted inside the structure, a hollow connector extending from said casing to the outside of the structure, an actuating rod extending longitudinally through said connector, said connector having openings therethrough, and an integral body of insulation filling said openings and covering the outside of said connector and substantially filling the space between said connector and actuating rod, the outside of said body of insulation being tapered.
12. An article of manufacture for use in fire-proof structures comprising a tubular connector, shoulders at opposite ends of the connector, and a layer of insulating material fast on the connector between said shoulders.

13. An article of manufacture for use in locks for fire-proof structures comprising a tubular connector, and a body of insulation

fast thereon to form a unitary element for insertion as a unit into the connector openings of such structures.

14. An article of manufacture for use in locks for fire-proof structures comprising a tubular connector, and a cylindrical layer of insulation fast thereon to form a unitary element for insertion as a unit into the connector openings of such structures.

15. An article of manufacture for use in locks for fire-proof structures comprising a tubular connector, and a cylindrical layer of insulation fast thereon to form a unitary element, said layer being partly within and partly without said connector.

16. An article of manufacture for use in locks for fire-proof structures comprising a tubular connector, and a cylindrical layer of insulation fast thereon to form a unitary element, said layer being partly within and partly without said connector, and integral ribs connecting the inner and outer portions of the layer of insulation through slots in said connector.

Signed by me at Ilion, N. Y., this 27th day of September, 1921.

ENOCH OHNSTRAND.
